(57) **CLAIM**

The ornamental design for a golf club, as shown and described.

DESCRIPTION

FIG. 1 is a front view of an ornamental design for a golf club, according to an embodiment of the design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front and top perspective view thereof; and,

FIG. 8 is a rear and top perspective view thereof.

The dash-dash-dash broken lines are included for the purpose of illustrating portions of the golf club that form no part of the claimed design. The dash-dot-dash broken lines are included for the purpose of illustrating boundary lines and form no part of the claimed design.

The break lines disclosed on the drawing views form no part of the claimed design.

1 Claim, 8 Drawing Sheets(56)
